UNITED STATES PATENT OFFICE.

RALPH T. OVERTON, OF STAATSBURG, NEW YORK.

FOUNTAIN BLACKING-BRUSH.

1,031,662.

Specification of Letters Patent. Patented July 2, 1912.

Application filed September 7, 1910. Serial No. 580,845.

To all whom it may concern:

Be it known that I, RALPH T. OVERTON, a citizen of the United States, residing at Staatsburg, in the county of Dutchess and 5 State of New York, have invented new and useful Improvements in Fountain Blacking Brushes, of which the following is a specification.

This invention relates to improvements in 10 brushes and the same is primarily adapted for employment as a dauber for shoes, stoves and similar articles to be polished, but of course the device is capable of being employed for other purposes, such as painting or the like.

The principal object of the present invention is to provide a fountain brush which is of an extremely simple construction, which has a valve for regulating the flow of the 20 liquid to the brush from the reservoir and which provides means whereby the said reservoir may be easily and quickly removed for refilling the same.

With the above and other objects in 25 view, which will appear as the description progresses, the invention resides in the novel construction and combination of parts hereinafter fully described and claimed.

In the accompanying drawings, Figure 1 30 is a side elevation of a fountain brush constructed in accordance with the present invention. Fig. 2 is a central longitudinal sectional view of the same. Fig. 3 is a bottom plan view, the bristles being removed 35 to more clearly illustrate the structure of the valve.

In the accompanying drawings the numeral 1 designates the improved fountain brush. This brush 1 comprises a handle 2 40 having one of its ends enlarged and rounded so as to provide for the reception of the bristles 3. This enlarged portion, designated by the numeral 4 is formed with a central orifice or opening communicating 45 with the bristles, and this opening is preferably reinforced through the medium of a metallic tube, the latter having its lower extremity provided with threads 6 and its bottom portion formed with a valve seat 7. 50 The valve seat 7 is provided upon both its inner and outer surfaces with suitable gaskets which are constructed of rubber, leather or some other suitable yieldable material. The numeral 8 designates the reser-

voir of the device. This reservoir has one 55 of its ends provided with a reduced cylindrical pipe extension 9, the same being provided with threads 10 which are adapted to coact with the threads 6, and the mouth of the said extension is adapted to bear 60 against the inner gasket so as to form a liquid-proof connection between the handle and the reservoir. When it is desired to remove the reservoir from the handle 2, when the device is being packed for refilling, shipment, etc., the threaded tubular extension may be provided with any suitable cap, which in this instance, it has not been deemed necessary to illustrate. The under 65 face of the enlargement 4 directly below the valve seat is provided with a hinged valve 11. This valve 11 comprises preferably a circular plate or disk and is pivoted adjacent its inner end or that portion nearest the handle of the dauber as designated by 70 the numeral 12. The central portion of the said valve is formed with a bail 13, and pivotally connected with the said bail is an operating rod 14. The inner face of the valve 75 may be provided with a coating of some 80 suitable material, such as rubber or the like, so as to fit tightly upon the lower gasket provided by the valve seat. The rod 14 is slidably mounted within an eye 15 formed upon the under face of the handle adjacent 85 its enlargement, and the extremity of the said rod is formed with a loop or other suitable finger grip 16 so that the rod may be 90 slid to open the valve. The rod 14 is further provided with an integrally formed collar 17, and positioned between this collar and the eye 15 is a helical spring 18. This spring 18 is adapted to exert pressure 95 between the eye and the collar, so as to normally retain the valve in its seated or closed 100 position, and thus prevent the leakage of the liquid contained within the receptacle 8, except when the rod is operated so as to allow the said liquid to flow to the bristles of the brush when the latter is to be operated, and it will be noted that the liquid 105 contacting the flattened valve will be distributed evenly to the bristles of the brush.

It will be noted by reference to Fig. 2 of the drawings that the bristles or hairs of the brush surrounding the hinged valve 11 are arranged at an inclination toward the face of the brush so as to provide a pocket

19 within which the liquid may be received and distributed to the remaining bristles of the brush when the latter is operated.

Having thus fully described the invention, what I claim as new is:—

In a blacking brush comprising a brush head having a transverse opening and a handle, means for securing a blacking receptacle in said opening, a valve pivoted to the under face of said brush head and adapted to open outwardly, brush bristles secured

to said brush head and surrounding said valve, and a spring controlled rod pivoted to said valve and movable rearwardly in the direction of the handle adapted to open and close said valve.

In testimony whereof I affix my signature in presence of two witnesses.

RALPH T. OVERTON.
